HINGE CONSTRUCTION

Clifford E. Brownell, Buffalo, N. Y., assignor of one-fourth to Ashley F. Wilson, East Aurora, and one-fourth to Erwin N. Wilson, one-fourth to Lyndon A. Wilson, and one-fourth to S. Shepard Wilson, all of Buffalo, N. Y.

Application September 28, 1946, Serial No. 699,976

7 Claims. (Cl. 16—172)

1

This invention relates to container closures and particularly to novel hinge means therefor.

The present invention provides a novel construction wherein a receptacle and a cover element therefor are provided with novel hinge formations whereby they may be readily assembled without the use of special tools or auxiliary securing devices, such as hinge wires or the like. While the invention is not thus limited, the construction proposed herein is particularly well adapted for use in the construction of domestic garbage cans, generally referred to as sanitary cans, wherein mechanism is provided for raising the cover or lid by the depression of a foot pedal.

In such constructions, a link is generally connected to the cover or lid for moving the same between closed and opened positions, and in the present construction such link or similar connection is availed of to prevent accidental disassembly of the hinge. The hinge construction of the present invention comprises merely two simple metal stampings so that, in addition to simplicity of assembly, the hinge is equally simple to fabricate.

While specific details of construction are illustrated in the drawing and described in detail in the following specification, it is to be understood that various mechanical modifications may be made without departing from the principles of the invention, which are limited only as defined in the appended claims.

In the drawings:

Fig. 1 is a top plan view of one form of a hinge element which is secured to a container or receptacle;

Fig. 2 is a side elevational view thereof;

Fig. 3 is a top plan view of a cooperating element which is fixed to the lid or cover of the receptacle;

Fig. 4 is a side elevational view thereof;

Fig. 5 is a side elevational view showing the elements of Figs. 1 through 4 in the position they occupy at the beginning of the assembly operation;

Fig. 6 is a view similar to Fig. 5 but with the parts moved further toward an assembled position; and

Fig. 7 is a view similar to Figs. 5 and 6 but with the parts still further advanced toward final assembled position.

Referring to Figs. 1 and 2, a generally cylindrical receptacle is indicated in dot and dash lines at 10, and a hinge element which is adapted to be rigidly secured thereto by welding, riveting, or the like is indicated generally at 11. Hinge ele-

2

ment 11 has a central web portion 12 for securing against the upper exterior wall of container 10 and a pair of parallel vertically extending flanges 13 and 14. Flanges 13 and 14 have, respectively, inwardly stamped annular flanges 15 and 16 which are co-axial and provide a pair of bearing trunnions.

Referring to Figs. 3 and 4, a complementary hinge element is designated generally 18 and is adapted to be fixed to an edge of a cover element which is indicated in dot and dash lines in Fig. 4 at 19. In the form contemplated in Fig. 4, cover element 19 is crowned and the hinge element may have a securing flange 20 which follows the contour of the interior of cover 19 so that it may be securely fixed thereagainst by welding, riveting, or otherwise. Adjacent flange 20, hinge element 18 has a channel portion comprising a web 22 and opposed side flanges 23 and 24. The outer end of web 22 is bent downwardly as at 26 and terminates in a semi-circular curl 27.

Referring again to Figs. 1 and 2, the outer ends of flanges 13 and 14 are arcuately shaped as at 28, their defining radius being concentric with trunnions 15 and 16. Below trunnions 15 and 16, flanges 13 and 14 are flat as at 30 in Fig. 2. The flanges 23 and 24 are preferably arcuate, as at 31 in Fig. 4, merely for the purpose of registering with the arcuate edges of flanges 13 and 14 to present a trim appearance.

As is shown in Figs. 3 and 4, web 22 of hinge element 18 has struck therefrom a pair of parallel flanges 34 and 35 which give bearing to a pivot pin, which may be a cotter pin or the like, which pin is engageable by a vertical cover operating link which is shown in dot and dash lines in Fig. 7 at 38. The manner in which cover link 38 operates to raise and lower the cover element is not important to a consideration of the present invention, save to state that when it is connected between flanges 34 and 35 it limits the cover element to a predetermined range of movement.

The manner in which the hinge elements 11 and 18 are assembled will now be described, it being understood that they are normally rigidly secured to the container and cover, respectively, before assembly. Referring to Fig. 5, hinge element 18 is placed in an inverted position beneath hinge element 11 as shown in full lines in Fig. 5, and hinge element 18 is then raised until its curl 27 is in the position indicated in dot and dash lines in Fig. 5. The cover and its hinge element 18 are then moved to the right to the full line position illustrated in Fig. 6, whereupon hinge element 18 may be dropped until its curl 27 rests

against trunnions 15 and 16 as indicated in dot and dash lines in Fig. 6

The next step in assembly comprises rotating the cover and its hinge element 18 in a counter-clockwise direction about the axis of trunnions 15 and 16, with curl 27 in engagement with the trunnions, to the position illustrated in full lines in Fig. 7. It will be noted that in this position, and in any further counterclockwise position of hinge element 18, the inside surface of web 22 is in sliding contact with the arcuate outer edges 28 of flanges 13 and 14, which engagement prevents movement of curl 27 away from trunnions 15 and 16.

Movement of hinge element 18 from the full line position of Fig. 7 to the cover-closed position shown in dot and dash lines in Fig. 7 is thus constrained to true pivotal movement about the axis of trunnions 15 and 16 and flanges 23 and 24 prevent disassembly in an axial direction. Subsequent pivotal connection of link 38 between flanges 34 and 35 of hinge element 18 constrains the cover element to pivotal movement from closed position to a full-open position which is short of, or at least not beyond, the full-line position of hinge 18 in Fig. 7. Accordingly, hinge element 18 cannot be disassembled from its pivotal connection with hinge element 11, excepting when such disassembly is desired, when it is effected by disconnecting link 38 and reversing the assembly procedure.

What is claimed is:

1. In a hinge construction for container closures, a hinge element for securing against the exterior surface of a container adjacent the upper edge thereof, said element comprising a central securing portion and a pair of parallel vertical outstanding flanges, co-axial journal means on said flanges, the outer edges of said flanges being arcuate concentrically with said journal means and the distance from the axis of said journal means to the lower edges of said flanges being substantially less than the radius of said outer edges, a second hinge element for securing to an edge of a cover element for the container and comprising, with the cover in closed position, a downwardly opening channel seating over said flanges and an end flange terminating in an upwardly facing arcuate portion concentric with said journal means and adapted to bear against the under surfaces thereof, the cover element being constrained to pivotal movement about the axis of said journal means throughout its normal opening and closing movements by engagement of the web portion of the channel against the arcuate edges of said flanges, said second hinge element being assembled with or removed from the first hinge by movement of the cover to abnormal inverted position wherein the web of said channel may be raised to said lower edges of the flanges to permit the arcuate portion of said end flange to be moved horizontally to or away from a position over said journal means.

2. In a hinge construction for container closures, a hinge element for securing against the exterior surface of a container adjacent the upper edge thereof, said element comprising a central securing portion and a pair of parallel vertical outstanding flanges, co-axial journal means projecting inwardly from each of said flanges, the outer edges of said flanges being arcuate concentrically with said journal means and the distance from the axis of said journal means to the lower edges of said flanges being substan-

tially less than the radius of said outer edges, a second hinge element for securing to an edge of a cover element for the container and comprising, with the cover in closed position, a downwardly opening channel seating over said flanges and an end flange terminating in an upwardly facing arcuate portion concentric with said journal means and adapted to bear against the under surfaces thereof, the cover element being constrained to pivotal movement about the axis of said journal means throughout its normal opening and closing movements by engagement of the web portion of the channel against the arcuate edges of said flanges, said second hinge element being assembled with or removed from the first hinge by movement of the cover to abnormal inverted position wherein the web of said channel may be raised to said lower edges of the flanges to permit the arcuate portion of said end flange to be moved horizontally to or away from a position over said journal means.

3. In a hinge construction for container closures, a hinge element for securing against the exterior surface of a container adjacent the upper edge thereof, said element comprising a central securing portion and a pair of parallel vertical outstanding flanges, co-axial journal means on said flanges, the outer edges of said flanges being arcuate concentrically with said journal means and the distance from the axis of said journal means to the lower edges of said flanges being substantially less than the radius of said outer edges, a second hinge element for securing to an edge of a cover element for the container and comprising, with the cover in closed position, a plate portion extending over said flanges and downwardly and terminating in an upwardly facing arcuate portion concentric with said journal means and adapted to bear against the under surfaces thereof, the cover element being constrained to pivotal movement about the axis of said journal means throughout its normal opening and closing movements by engagement of said plate portion against the arcuate edges of said flanges, said second hinge element being assembled with or removed from the first hinge by movement of the cover to abnormal inverted position wherein the plate portion may be raised to said lower edges of the flanges to permit the arcuate terminal portion of said second hinge element to be moved horizontally to or away from a position over said journal means.

4. In a hinge construction for container closures, a pair of cooperating hinge elements, one for securing to a container and the other for securing to a closure therefor, one of said elements comprising spaced flanges and journal means, said flanges having arcuate edges concentric with said journal means, the other of said elements having an internally arcuate portion for bearing engagement with said journal means and a relatively flat surface portion facing said internally arcuate portion and adapted to bear against the arcuate edges of the flanges of said one element during pivotal movement of the two elements to retain the internally arcuate portion and the journal means in co-axial bearing engagement.

5. In a hinge construction for container closures, a pair of cooperating hinge elements, one for securing to a container and the other for securing to a closure therefor, one of said elements comprising spaced flanges and journal means, said flanges having arcuate edges concentric with said journal means, the other of said

elements having an internally arcuate portion for bearing engagement with said journal means and a relatively flat surface portion facing said internally arcuate portion and adapted to bear against the arcuate edges of the flanges of said one element during pivotal movement of the two elements to retain the internally arcuate portion and the journal means in co-axial bearing engagement, the arcuate edges of said flanges terminating in a portion of reduced dimension outside the normal arc of movement of said cover to permit assembly and disassembly of the internally arcuate portion and the journal means in such position.

6. In a hinge construction for container closures, a pair of cooperating hinge elements, one for securement to a container and the other for securement to a closure therefor, one of said elements comprising spaced flanges and journal means, said flanges having arcuate outer edges concentric with said journal means, the lower edge of said flanges having portions thereof at a lesser distance from the axis of the journal means than the radius of the arcuate edges, the other of said elements having an internally arcuate portion bearing upwardly against said journal means when the cover is in closed position and a relatively flat surface portion facing said internally arcuate portion and extending over said flanges to bear against the arcuate edges of the flanges of said one element during pivotal movement of the two elements in opening and closing the cover to retain the internally arcuate portion and the journal means in coaxial bearing engagement, said other element being movable upwardly with the cover in inverted position by

reason of said lower edge portions to effect assembly and disassembly of said internally arcuate portion.

7. In a hinge construction for container closures, a pair of cooperating hinge elements, one for securement to a container and the other for securement to a closure therefor, one of said elements comprising spaced flanges and journal means, said flanges having arcuate edges concentric with said journal means, the other of said elements having an internally arcuate portion for bearing engagement with said journal means and a relatively flat surface portion facing said internally arcuate portion and adapted to bear against the arcuate edges of the flanges of said one element during pivotal movement of the two elements to retain the internally arcuate portion and the journal means in co-axial bearing engagement, said flat surface portion having side flanges extending over the flanges of said one element to prevent undue relative axial movement of said two elements.
